CLOSURE MEANS FOR RECEPTACLES

Vernon E. Cornell, Garfield Heights, Ohio, assignor to Cornell Securities Corporation, Cleveland, Ohio, a corporation of Delaware

Application January 31, 1934, Serial No. 709,221

9 Claims. (Cl. 220—61)

My invention relates to containers or receptacles and closures therefor. One object of the invention is to provide improved means of simple construction for securely but detachably clamping the cover of a receptacle or drum to its rim or circumferential bead in a fluid tight manner.

Another object of the invention is to provide a sealing means for the cover of a receptacle having an improved clamping mechanism arranged to secure and seal the cover in position without imparting strain or pressure on the cover walls.

Another object of the invention is to provide a split sealing ring arranged to externally engage portions of a cover and receptacle and having within the cover area improved operating connections or mechanism between the ring ends operable independently of and without engagement with the walls of the cover or receptacle for clamping the ring in position and releasing it.

Another object of the invention is to provide a split sealing ring for the cover of a receptacle arranged to externally engage portions of the cover and receptacle and having an improved mechanism within the periphery of the cover and comprising co-acting elements between and connected to the ring ends arranged to draw the ends together and effect a circumferential contraction of the ring without causing outward pressure on either or both of the ring ends.

Another object of the invention is to provide a split sealing ring for securing a cover to a receptacle and arranged to externally engage portions of the cover and receptacle and having an improved mechanism within the area of the cover and comprising co-acting elements connected to the ring ends and operable in contracting or expanding the ring along an imaginary arc within the ring, so that in clamping the ring in position it is contracted substantially uniformly throughout its circumference and its ends are moved into aligned end to end relation.

A further object of the invention is to provide an improved closure sealing means comprising a split, contractible and expandible ring having between its ends and within its area a thrust member and means for operating it endwise to contract or expand the ring and laterally to lock it in one position or to release it for endwise movement.

A still further object of the invention is to provide a split contractible and expandible ring having between its ends and within its area op-

erating connections which contract and expand the ring and lock it in either position.

Other and further objects and advantages of the invention will be understood from the following description considered in connection with the accompanying drawings, wherein:

Fig. 1 is a plan view of a container provided with a closure means embodying my invention.

Figs. 2, 3 and 4 are sections on the lines 2—2, 3—3 and 4—4, respectively, of Fig. 1.

Fig. 5 is a plan view showing the position of the parts and the ring when the latter is partially expanded, a portion of the crank being removed to facilitate the illustration.

Fig. 6 is a perspective view of the rack member.

Figs. 7 and 8 are plan views showing modified forms of construction.

Fig. 9 is a perspective view of the rack member shown in Fig. 8.

Figs. 10 and 11 are sections on the lines 10—10 and 11—11, respectively, of Fig. 8.

Fig. 12 is a plan view showing a different embodiment of the invention.

Figs. 13 and 14 are sections on the lines 13—13 and 14—14, respectively, of Fig. 12.

Fig. 15 is a perspective view of the gear element, in inverted position, shown in Figs. 12, 13 and 14.

Fig. 16 is a plan view of a ring and operating connection therefor showing a further embodiment of the invention.

Figs. 17, 18 and 19 are sections on the lines 17—17, 18—18 and 19—19, respectively, of Fig. 16.

Fig. 20 is a fragmentary plan view showing the position of the parts when the ring is expanded.

Fig. 21 is a fragmentary perspective view showing the lug and rack and guides thereon.

In the drawings, referring particularly to Figs. 1 to 6, inclusive, 1 indicates a receptacle, barrel or drum such as ordinarily used for shipment of solids, semi-liquids and liquids, including foods, oils, grease and the like.

In the form shown, the open end of the receptacle 1 is formed with an outwardly rolled portion, providing a false bead 2 to reinforce the upper end of the receptacle and to form a seat for a cover 3. The cover 3 is preferably cup-shaped and provided with an outwardly extending flange 4, of arc-shape in cross section to fit the upper portion of the bead 2.

Any form of packing ring 2' is inserted between the bead 2 and flange 4, so that when a sealing ring, such as indicated as an entirety at 5, is secured in position the cover is clamped to the bead 2 and sealed in a liquid tight manner.

As the ring may be readily clamped and un-

clamped, the cover 3 is removable for filling or refilling of the receptacle.

The ring 5 is split to provide two ends to permit of its contraction and expansion and is substantially U-shaped in cross section, whereby it may be applied externally into embracing relation to the bead 2 and flange 4 and when contracted its upper and lower walls may exert a substantially uniform clamping pressure throughout its circumference against these parts. The ring 5 is preferably continuous from end to end and formed of a single section of metal rolled into U-shape. The metal of the ring 5 is resili-
ent and preferably normally tends to expand circumferentially to a position which permits of its assembly and removal. 6, 6' indicate lugs extending inwardly from the upper wall of the ring adjacent its ends and parallel to the cover top when the ring is in position. Each lug may be formed integrally with or welded or riveted to the ring wall. The inner portions of the lugs 6, 6' may be off-set into a plane below the upper ring wall, if desired. The operating mechanism, indicated as an entirety at 1, is preferably arranged in either arrangement of the lugs so that it, except the operating crank thereof, will not project above the upper ring wall. By preference, the opposed edges of the lugs 6, 6' are provided with interlocking elements, such as a notch 8 (having converging side walls) formed in one lug and a complementary projection 8' on the other lug, which elements prevent lateral relative movements of the ring ends when the clamping or operating mechanism 1 contracts the ring into its final clamping position. The clamping or operating mechanism 1 is arranged to effect a movement of the ring ends, in contracting or expanding the ring along an imaginary arc substantially concentric to an axis, at approximately the opposite side of the ring. As a result of this movement, the opposite portions of the ring expand the contract about this axis, so that (a) any tendency of either ring end to be forced outwardly and project beyond the other ring end is eliminated and (b) the ring is contracted substantially uniformly throughout its circumference with the result that tight sealing is effected between the cover flange 4 and bead 2 at all points. The operating mechanism 1 is constructed to provide a means for locking the ring ends in clamped-on position, in the form of construction shown in Figs. 1 to 7, inclusive, and in the form of construction shown in Figs. 8 to 14, inclusive, it is constructed to also provide means for locking the ring ends in their expanded position, which facilitates handling of the ring.

In Figs. 1 to 6, inclusive, the combined operating mechanism and locking means comprise the following: 9 indicates a rack member having a tail 9' suitably pivoted at 9x to the lug 6 (preferably on its lower face or side) and extending from the pivot 9x in the direction of and beyond the lug 6'. 10 indicates a crank fixed to a shaft 11, which rotates in an opening 12 formed in the lug 6', the axis of the opening 12 being disposed inwardly from the ring 5 a distance slightly greater than the axis of the pivot for the tail 9'. The shaft 11 is provided in a plane below the lug 6' with a pinion 13 and below the pinion 13 it is provided with a collar 14 which forms a roller for a purpose later set forth. The shaft 11, pinion 13 and collar 14 may be formed integrally.

The rack member is formed with an elongated slot or opening 15, preferably curved substantially concentric to the ring axis and having at its inner

end an inwardly extending off-set opening 15'. As shown the openings 15, 15', merge to permit movement of the pinion 13 and collar 14 from one opening to the other. The outer longitudinal wall of the opening 15 and outer side wall of the off-set opening 15' are provided with gear teeth forming a continuous rack 16 with which the pinion 13 meshes, whereas the inner longitudinal wall of the opening 15 and inner side wall 19 of the off-set opening 15' are smooth and connected to form a rolling surface or guide 17 for the collar 14, to maintain the pinion 13 in engagement with the rack, the latter wall also forming a seat for the collar 14 as later set forth. That portion of the rack member which forms the guide and seat for the collar 14, between the opposite free ends of the rack 16 is off-set downwardly so as to be in the plane of the collar. The lower end of the shaft 11 is provided with a washer 18, held in place by the riveted over end of the shaft. The washer 18 bears against the lower face of the guide carrying portion of the rack member 9 and co-acts with the crank 10 to prevent endwise movement of the shaft and to hold the parts in operative relation. The crank 10 may be held on the upper end of the shaft 11 by riveting over such end or by means of a cotter pin. When desired, the crank may be detachably connected to the shaft 11. With these parts assembled, they prevent relative movement of the ring ends laterally of the plane of the ring when the ends are being brought together or moved away from each other, as later set forth. By turning the crank 10 in a counter-clockwise direction, as viewed in Fig. 1, the pinion through its travel on the rack 16 will impart a thrust movement on the rack member 9 substantially endwise relative to the lug 6' and thus cause an expansion of the ring. By turning the crank in a clock-wise direction, the pinion 13 will move the rack member in the opposite direction and thus cause a contraction of the ring, as shown in Fig. 1. To effect a locking of the parts, with the ring in position on the cover flange and bead, I curve the inner side wall 19 of the off-set opening 15' on a radius struck from the axis of the pivot 9x for the tail 9'. Accordingly, in the further rotation of the pinion 13 after reaching that portion of the rack at the inner end of the opening 15, its engagement with the rack on the outer wall of the off-set opening 15' will cause the rack member to swing outwardly about its pivot 9x relative to the shaft 11, the curved wall 19 permitting of such movement and forming a seat for the collar, so that the latter locks the rack member against inward movement due to the compression of the ring in opposition to its normal resiliency. To permit of this movement of the rack member, the rack 16 is curved about the inner end of the inner side wall 19. In unclamping the ring, rotation of the pinion 13 counter-clockwise will first swing the rack member inwardly relatively to the shaft 11. Such movement will move the inner end of the wall 19 beyond the collar 14 and unlock the latter, following which continued rotation of the pinion 13 by the crank 10 will cause it to traverse the rack, the effect of which will be to expand the ring 5, and thus permit removal of the cover 3. The outer end portion of the crank 10, when in the ring clamping position, may be engaged behind the down-turned end of a clip 20 carried by the upper wall of the ring 5 (see Fig. 1), the resiliency of the crank and clearance between the parts being sufficient to permit the crank to be deflected downwardly to ride such down-turned end. The

end wall of the off-set opening 15' may serve as a stop to limit the outward swinging of the rack member.

Fig. 7 shows a modified form of construction in which the rack teeth are provided on the inner side wall of the opening 15 and inner side wall of the opening 15' and the guide 17' for the collar 14 extends along the outer sides of these openings. In this arrangement the pitch line of the rack on the inner side wall of the opening 15' and the opposed outer side wall 19' are concentric to the axis of the rack member pivot 9x so that in the movement of the crank 10 to the extreme end of its movement, the pinion 13 swings the rack member laterally and becomes locked behind the inner or free end of this portion of the rack. In this arrangement, the crank 10 is turned clockwise to expand the ring 5 and counter-clockwise to contract it.

Figs. 8, 9, 10 and 11 show a further modified form of construction in which the ring is locked in its clamped-on position and locked in its un-clamped or expanded position. This form of construction is also further modified in that the rack and guide wall for the pinion and collar are reversed as compared to the arrangement of these parts in Figs. 1 to 6, inclusive. In providing a locking means for the ring in its expanded condition, the ring ends are held in fixed relation, which permits the ring to be easily handled, for example, when placing it in position for clamping and sealing the cover 3 or removing the ring from the cover after the latter has been released prior to its removal. In these views, the rack member, indicated at 9a, is pivoted at 9a' to the lug 6, and is formed with a longitudinally extending curved opening 15a and off-set openings 15a' at the opposite ends thereof; also, the rack teeth 16' are provided on the inner side wall of the opening 15a and inner side walls of the openings 15a'; and the guide 17' for the collar 14 to roll on and maintain the pinion in mesh with the rack 16' is provided on the opposed walls of these openings. As shown, the outer side and outer end portions of the rack member carrying the guide wall are off-set downwardly to dispose this wall in the plane of the collar. In this arrangement, the pitch lines for the rack teeth on the inner sides of the openings 15a' and the opposed guide walls are concentric to the axis of the pivot 9a', so that in the movement of the crank 10 to the extreme end of its movement in either direction, the pinion 13 swings the rack member laterally and becomes locked behind the teeth at the end of the adjacent side wall and thus prevents the pinion 13 and collar 14 from entering the opening 15a. In this form of construction, as viewed in Fig. 8, the crank 10 is turned in the clockwise direction to expand the ring and in a counter-clockwise direction to contract it, and operation of the crank will rotate the pinion, which being fixed to the crank shaft 11, will move the rack member endwise and thus contract or expand the ring according to the direction of movement of the crank. When the construction is provided with means to lock the ring ends in expanded relation, the ring is expanded beyond its normal position so that the resiliency of the ring to return to its normal position may be utilized to maintain the parts in their locked relation. For this purpose, the opening 15a is arranged so that when the pinion 13 is at the inner end thereof the ring is contracted in opposition to its resiliency and when the pinion 75 is at the outer end of the opening the ring is ex-

panded in opposition to its resiliency. When the pinion is rotated in either direction it will traverse the opening 15a and be guided into the adjacent off-set opening 15a' behind the inner end of the rack therein and continued rotation of the pinion 5 will cause the rack member to swing laterally (outwardly) about its pivot 9a' relative to the shaft 11. It will thus be seen that when the pinion 13 is in either off-set opening 15a', the ring ends are biased in clamped-on position or in expanded position beyond their normal position, so that the tendency of the ring to return to its normal position serves to hold the pinion in either opening 15a' and prevent return of the rack member.

Figs. 12, 13 and 14 show a different embodiment of the invention in which the operating mechanism is simplified in such manner that the rack and the pinion element which meshes therewith co-operatively function to effect contraction of the ring when embracing the container bead and cover flange or expansion of the ring and locking thereof in either position; that is, I combine the rack and pinion and locking means so that a swingable rack member is eliminated. In these views the lug 6 is provided with an extension 21 which is preferably formed integrally therewith. The extension is off-set downwardly so as to lie in a plane below the lug 6' and extends beyond the latter, the length of the extension being such that its outer end does not move past the lug 6' when the ring is expanded for a reason which will later be apparent. One side wall of the extension 21 (preferably its outer side wall) is curved on an arc preferably struck approximately from a radius of the ring and is provided with a rack of the "Geneva stop tooth type", having notches 22 connectedly spaced by arc-shaped lands 23. The shaft 11a for the crank 10a is rotatably mounted in the lug 6' and carries at its lower end, in a plane below the extension 21, a disk 24 which preferably overlaps the extension 21 as shown in Fig. 13. Between that portion of the shaft which rotates in the lug 6 and the disk 24, the shaft 11a is shaped to form a portion 24a concentric to its axis and between the ends of the concentric portion, at one side of the shaft axis, I provide a tooth 25, preferably comprising a round head having a shank 26 extending through an opening in the disk and riveted over at its lower end. As will be understood, the tooth 25 enters the notches 22 and the concentric portion 24a engages with and rotates in the lands; accordingly, turning of the crank clockwise as shown in Fig. 12 will effect engagement of the tooth 25 with the walls of the notches 22, successively, and cause expansion of the ring 5 and turning of the crank in the opposite direction will cause a contraction of the ring. In this form of construction the extension forms the rack member and is rigidly connected to the lug 6. The notches 22 are arranged so that the tooth engages with one end notch when the ring is fully contracted to seal the cover flange 4 to the bead 2 and with the other end notch when the ring is expanded. As the ring ends are locked against relative movement when the tooth 25 is in each notch, it will be seen that the ring will be locked when in either contracted position or expanded position. By preference, the outer end of the lug 6' is provided with a down-turned flange 26 arranged to engage the inner edge of the extension 21 to resist outward pressure thereon and relieve the lug 6 of undue strains.

In Figs. 16 to 21, inclusive, I show another em- 75

bodiment wherein certain of the parts are reversed in that the rack and pinion guide are provided on one lug, the thrust member is pivoted to the other lug and the pinion and collar are mounted on the thrust element. In these views 5 6b, 6b' indicate lugs suitably fixed to the upper wall of the ring 5 and projecting inwardly therefrom, adjacent its ends, respectively. By preference, the opposed edges of the lugs 6b, 6b', are provided with complementary interlocking elements 8b, 8b', similar to the elements already referred to. 26 indicates a thrust member pivoted at one end at 26a to the lug 6b' and rotatably supporting at its opposite ends a shaft 11b provided with a pinion 13b and a collar 14b therebelow. The thrust member preferably comprises a pair of links 26, 26' disposed above and below the lugs 6b, 6b', the pivot 26a serving to pivotally connect both links at one end to the lug 6b' and 20 a spacer 27 surrounding the pivot 26a and between the lug 6b' and lower link 26' being provided for a purpose which will later be apparent. The shaft 11b is rotatably supported in the opposite ends of the links. The pinion 13b and collar 14b are disposed between the links and are preferably formed integrally with the shaft 11b. The upper end of the shaft is provided with an enlarged head 11c, shaped to provide a detachable connection for a crank 10b. The lower end 30 of the shaft 11b may be riveted over. The lug 6b is elongated circumferentially of the ring and formed with an elongated opening 15b, preferably curved approximately concentrically to the ring axis, and at its opposite ends with off-set 35 openings 15b' preferably extending inwardly, to permit the links to swing laterally at the end of their thrust movement in either direction, as later set forth. The outer wall of the opening 15b and outer side walls of the openings 15b' are provided with gear teeth forming a continuous rack 16b. The inner side wall of the opening 15b and inner side walls of the openings 15b' form guides 17b, 19b, for the collar 14 and by engagement therewith, they maintain the pinion in mesh 40 with the rack 16b. That portion of the lug 6b between the opposite ends of the rack 16b and carrying the guides 17b, 19b is off-set downwardly so that the guides are disposed in the plane of the collar 14b; also, the inner side walls 19b of the 45 openings 15b' are curved on radii struck from the axis of the pivot 26a so that when the pinion engages the rack on the outer side wall of either opening 15b' and the thrust links 26' are swung laterally relative to the pinion shaft 11b, these 50 walls will engage the collar 14 and maintain the pinion in mesh with the rack and in turn lock the links in their laterally operated position. With the ring 5 in position clamping the cover flange 4 to the receptacle bead 2, as shown in Fig. 16, the engagement of the collar 14b with the adjacent wall 19b, under the tendency of the ring to expand, will prevent outward swinging movement of the links 26'. If now the crank 10b is turned, the pinion 13b will (a) through its engagement with the rack on the outer side wall 55 of the opening 15b' first swing the links outwardly, thus unlocking the links 26' from the lug 6b and (b) through its engagement with the rack on the outer side wall of the opening 15b cause an endwise thrust movement of the links 26', the effect of which is to expand the ring 5. If the operation is continued the pinion 13b will engage the rack of the outer side wall of the other opening 15b' and cause the links to swing inwardly, thus disposing the collar 14b in engagement with

the adjacent wall 19b, and locking the links against swinging movement outwardly. If now the crank 10b is turned clockwise, the pinion will first swing the links outwardly, then effect a thrust movement thereon and upon reaching the other opening 15b', it will swing the links inwardly and lock them against outward movement. 5

From the foregoing description it will be seen that in Figs. 1 to 15 the rack member and in Figs. 16 to 21, the links 26' serve as a thrust element between the ring ends or the lugs fixed thereto. As the thrust movement on the ring ends, in contracting or expanding the ring, is effected without outward or inward pressure on these ends or walls of the cover, the opposite portions of the ring are relatively moved substantially uniformly in either direction. It will also be noted that in Figs. 1 to 11, and 16 to 21, inclusive, the thrust element is pivoted to one lug and swings laterally when the collar and pinion are 20 guided into one of the off-set openings and when so moved, by reason of the engagement of the pinion or collar with one side wall of the adjacent off-set opening (the collar in Figs. 1 to 6 and 16 to 21 and the pinion in Figs. 7 to 11) it operates as a releasable dog to lock the ring in one 25 position. It will further be noted that the same elements are co-operatively related and constructed to contract and lock or expand and also lock the ring by the single operation of the crank 30 in one direction; and when the ring is in either position, the operation of the crank in the opposite direction will unlock the ring and operate it to its other locked position.

It will be noted that, in the several different 35 embodiments of my invention here presented, the means employed to lock the clamp ring in position, either open or closed, such as the off-set openings or recesses 15', 15a' and 15b', with the walls of which certain parts, such as the collars 40 14, 14b, engage when the parts come into locking position, take the strains tending to move the clamp into a different position from that in which it is locked.

Provision is preferably made to seal the operating connections against unauthorized operation. 45 For example, in Figs. 1, 2, 7 and 8 the clip 20 may be provided with an opening 28 which registers with an opening 29 in the crank 10, so that when the crank 10 is disposed in the clip, a wire may be passed through the openings and the ends thereof sealed by a lead slug. In Figs. 16 and 17 I provide aligned openings 30 in the links 26' and an opening 31 in the lug 6b. These openings are arranged to register when the ring 5 is mounted on the receptacle and contracted to secure the cover liquid-tight thereto, and to receive a wire 32, the ends of which may be sealed by a lead slug 33. In this latter arrangement, the crank may be detached when the receptacle 50 is transported. In the forms of construction shown in Figs. 1, 7 and 12, if it is desired to detach the crank during transportation, the openings are formed in the thrust element and the lug relative to which it moves endwise. 65

To those skilled in the art to which my invention relates, many changes in construction and widely differing embodiments and applications of the invention will suggest themselves without departing from the spirit and scope thereof. My 70 disclosures herein are purely illustrative and are not intended to be in any sense limiting.

What I claim is:

1. The combination with a receptacle and a cover having related annular portions, of a split 75

channeled clamping ring adapted to be contracted and expanded circumferentially and arranged to embrace said annular portions for securing them together when the ring is contracted, and means between the ring ends for contracting and expanding the ring and for locking the ring in one position, extending inwardly from the ring adjacent its respective ends and comprising a thrust member pivotally mounted at one end on one lug, a rack provided on the other lug, a pinion mounted on the opposite end of said thrust member arranged to mesh with said rack, means for maintaining said pinion in mesh with said rack and a device for rotating said pinion.

2. The combination with a receptacle and a cover having related annular portions, of a split channeled clamping ring adapted to be contracted and expanded circumferentially and arranged to embrace said annular portions for securing them together when the ring is contracted, and means between the ring ends for contracting and expanding the ring and for locking the ring in one position, said means including lugs extending inwardly from the ring adjacent its respective ends, a thrust member pivotally mounted at one end on one lug, a rack provided on the other lugs and provided with a guide wall, a shaft mounted on the other end of said thrust member and provided with a pinion arranged to mesh with said rack and a portion engaging said guide wall for maintaining said pinion in engagement with said rack, and a device for rotating said shaft.

3. The combination with a receptacle and a cover having related annular portions, of a split channeled clamping ring adapted to be contracted and expanded circumferentially and arranged to embrace said annular portions for securing them together when the ring is contracted, and means between the ring ends for contracting and expanding the ring and for locking the ring in one position, said means including lugs extending inwardly from the ring adjacent its respective ends, a thrust member pivotally mounted at one end on one lug, comprising a pair of links disposed above and below said lugs and pivotally connected at one end to one lug, the other lug being formed with an elongated opening and provided with a rack, a shaft mounted in the opposite ends of said links and carrying a pinion arranged to engage said rack and a device for rotating said shaft.

4. The combination with a receptacle and a cover having related annular portions, of a split channeled clamping ring adapted to be contracted and expanded circumferentially and arranged to embrace said annular portions for securing them together when the ring is contracted, and means between the ring ends for contracting and expanding the ring and for locking the ring in one position, said means including lugs extending inwardly from the ring adjacent its respective ends, a thrust member pivotally mounted at one end on one lug and comprising a pair of links above and below said lugs and pivotally connected at one end to one lug, the other lug being formed with an elongated opening and an off-set opening at one end thereof, a continuous rack provided on adjacent side walls of said openings, a shaft carried by the opposite end of said links and provided with a pinion arranged to travel along said rack to effect a substantially endwise movement of said links to contract or expand said ring and to swing the links laterally at the end of their endwise movement

and a device for rotating said shaft, and a wall on the opposite side of said off-set opening arranged to co-operate with the rack to lock the links when swung laterally.

5. The combination with a receptacle and a cover having related annular portions, of a split channeled clamping ring adapted to be contracted and expanded circumferentially and arranged to embrace said annular portions for securing them together when the ring is contracted, means between the ring ends for contracting and expanding the ring and for locking the ring in either position, said means including lugs extending inwardly from the ring adjacent its respective ends, a pair of links above and below said lugs and pivotally connected at one end to one lug, the other lug being formed with an elongated opening and off-set openings at the ends thereof, a continuous rack provided on adjacent side walls of said openings, a shaft carried by the opposite end of said links and provided with a pinion arranged to travel along said rack to effect a substantially endwise movement of said links to contract or expand said ring and to swing the links laterally at the end of their endwise movement in either direction and a device for rotating said shaft, and a wall on the opposite side of each of said off-set openings arranged to co-operate with the rack to lock the links when swung laterally.

6. The combination with a receptacle and a cover having related annular portions, of a split channeled clamping ring adapted to be contracted and expanded circumferentially, and engageable with said annular portions for securing them together, means for contracting and expanding said ring, comprising members carried by the ring ends, one of said members being swingably mounted on the adjacent ring end, one of said members consisting of a wall formed with an opening having an elongated portion and an inwardly off-set portion at one end thereof, the corresponding sides of said portions being provided with a continuous rack, and a pinion rotatably supported by the other member and arranged to mesh with said rack, and means for rotating said pinion to cause relative movement of said members during traverse of the pinion through the elongated portion of said opening and swinging movement of said swingable member during traverse of said pinion through the off-set portion of said opening, whereby one side wall of said off-set portion is interposed between said pinion and the pivot for said swingable member and operates to lock the members in a predetermined position.

7. The combination with a receptacle and a cover having related annular portions, of a split channeled clamping ring adapted to be contracted and expanded circumferentially and engageable with the said annular portions for securing them together when the ring is contracted thereon, lugs extending inwardly from the ring adjacent each end thereof, intermeshing gear elements directly connected to the aforesaid lugs and arranged to either contract or expand the ring at will as they intermesh, and means for locking the clamping ring in the position to which it is moved by the gearing and also relieving the gearing from direct strain due to tendency on the part of the ring to return to the position from which it was moved, comprising an off-set opening on one gearing element with a bearing surface and a contact portion carried by the other gear element adapted to come into engagement

with the said bearing surface at the conclusion of the movement of the ring by the gearing elements.

8. The combination with a receptacle and a cover having related annular portions, of a split channeled clamping ring adapted to be contracted and expanded circumferentially and engageable with said annular portions for securing them together when the ring is contracted, and means between the ends of the ring for contracting and expanding said ring, said means comprising a member provided with a rack and a member provided with a pinion in mesh with said rack, one of said members being swingably supported on the adjacent ring end, one end of said rack being curved laterally inwardly, and a guide opposite the rack and having a shoulder opposite the curved portion of the rack to permit the pinion when moved into meshing relation with the laterally curved end of the rack to swing the said swinging member laterally and lock said members in fixed relation.

9. The combination with a receptacle and a cover having related annular portions, of a split channeled clamping ring adapted to be contracted and expanded circumferentially and engageable with said annular portions for securing them together when the ring is contracted, and means between the ends of the ring for contracting and expanding said ring, said means comprising a member provided with a rack and a member provided with a pinion in mesh with said rack, one of said members being swingably supported on the adjacent ring end, each end of said rack being curved laterally inwardly to permit the pinion when moved into meshing relation with either laterally curved end of the rack to swing said swinging member laterally, and a guide opposite the rack and having a shoulder opposite the curved portion of the rack whereby said members are locked in fixed relation when said ring is in either its contracted or expanded position.

VERNON E. CORNELL.
